United States Patent Office.

JOHN W. ROGERS, OF DECATUR, ILLINOIS.

Letters Patent No. 75,703, dated March 17, 1868.

IMPROVED TUYERE.

The Schedule referred to in these Letters Patent and making part of the same.

TO ALL WHOM IT MAY CONCERN:

Be it known that I, JOHN W. ROGERS, of Decatur, in the county of Macon, and State of Illinois, have invented certain new and useful Improvements in Tuyeres; and I do hereby declare the following to be a full, clear, and exact description of the same, reference being had to the accompanying drawings, making a part of this specification, in which—

Figure 1 represents a perspective view of the tuyere.

Figure 2 represents a longitudinal vertical section through the same; and

Figure 3 represents a vertical transverse section.

Similar letters of reference, where they occur in the separate figures, denote like parts in all of the drawings.

I am aware that in tuyeres, the top has been raised up so as to bring the draught-issues above the surface where the ashes and light cinders deposit, but only at the opposite sides. This causes a dead space or eddy below where the cross-blasts meet, and a consequent slack in the fire where it is needed most. The difficulty in making a blast-opening in the bottom of the depression is that the ashes and fine cinder choke it up.

My invention consists in combining with the side-issues or cross-blast, a central issue slightly elevated, so that the ashes and cinder will roll off from the blast-issue in the depression, and I thus avail myself of all the advantages of central and side-issues or blasts, without encountering the difficulties incident to clogging or choking in a central sunken issue.

And my invention further consists in the use of weighted, self-acting valves, so arranged, in connection with the body of the tuyere, as to admit air enough to keep the fire going when the blast is off, and to allow the accumulation of ashes, &c., in the interior to drop out.

To enable others skilled in the art to make and use my invention, I will proceed to describe the same with reference to the drawings.

The tuyere may be cast in two parts, viz, an upper part, A, and an under part, B, the two parts being held together by their flanges *a b*, bolted together. The line of partition of the two parts may pass centrally through the wind or blast-pipe C, thus making the moulding and casting of the two parts very simple. The interior of the under portion is of a pot-shaped form, and it, as well as the interior of the upper portion, has no sharp or angular lines to impede the force of the blast through the tuyere. The top of the upper portion A is swelled or ridged up, or crowned, as shown at *c*, with a central depression across the crown or valley, as at *d*, and in the bottom of this valley there is a raised portion, *e*, through which the central blast or issue comes by the opening *f* therein. The light cinders and ashes will roll from the apex *e* into the lower portions *d*, and thus prevent this central-blast opening from getting choked up. The side-blasts come through openings *g g*, in the ridged-up portions *e e* of the top, A, and I thus get both vertical and lateral cross-blasts. At the bottom of the under portion B, through which there is an opening, *h*, there is hung, as at *i*, a weighted or overpoised valve, *j*, which closes and holds closed said opening, until the accumulated ashes or light cinder inside is sufficient to open it against the action of the weight or overpoise *k*, or until aided by the user to so open, for the purpose of allowing the ashes, cinder, &c., to drop out, and when relieved the valve immediately closes again. In or through the side or upper portion of the part B; there is also an opening, *l*, controlled by a weighted valve, *m*, pivoted at *n*. This valve, by its counterpoise *o*, stands open until the blast is put on, and then the force of the blast closes it and holds it closed, as seen by the red lines at fig. 2. When the blast is shut off, the valve swings and discloses the opening *l*, through which air passes to keep the fire "alive" whilst the blast is off. The ridged-up portions *e e*, instead of terminating at or immediately over the blast-openings *g g*, may project over and beyond said openings, so that they may serve, as seen at *e' e'*, as a protection to said blast-orifices, in keeping the ashes and cinders out of them; and thus projected over the blast-jets, they serve as directors to the blast, throwing the jets of air and the flame more into or towards a common centre.

Having thus fully described my invention, what I claim therein as new, and desire to secure by Letters Patent, is—

1. The upper portion A of the tuyere, constructed as described, and having the blast-openings arranged therein, substantially as set forth.

2. I claim also the pot-shaped under portion of the tuyere, having the weighted valves *j m*, arranged upon it, as and for the purpose herein described and represented.
